UNITED STATES PATENT OFFICE.

ATTILIO ZANCHI, OF SEVESO-SAN PIETRO, ITALY, ASSIGNOR TO THE FIRM FRATELLI SCHWARZENBACH & CO., OF SEVESO-SAN PIETRO, ITALY.

LOOM FOR WEAVING FINE FABRICS.

Application filed December 11, 1922. Serial No. 606,151.

To all whom it may concern:

Be it known that I, ATTILIO ZANCHI, a subject of the King of Italy, residing at Seveso-San Pietro, Italy, have invented 5 certain new and useful Improvements in Looms for Weaving Fine Fabrics, of which the following is a specification, reference being had therein to the accompanying drawing.

10 In order to be able to run weaving looms at higher speeds and to raise thereby the output, it has already been proposed to effect the beating up of the weft by means of an open reed or comb which oscillates about a rocking shaft situated below the weft and between the batten and the point where the weft is beaten up, which rocking shaft is also moved in a vertical direction; the batten being provided with the closed reed 15 which in this case has only to guide the warp threads and which forms thus only a guide reed or slay.

These known constructions of looms are, however, not suitable for weaving fine materials such as silk. With these constructions the teeth of the comb are withdrawn from the warp threads at the point where the weft is beaten up or at a point lying 20 close to said spot by moving the comb directly in a downward direction. The warp threads are spread apart by the movement of the comb in order to beat up the weft, as the warp threads are at a greater distance from each other when they leave the guide 25 reed than in the woven fabric, the comb, however, has the same width as the reed. When the comb is withdrawn from the warp near the beating up point the warp threads which have been spread apart will with 30 great force take up their normal position and will thereby wipe against the points of the teeth of the comb whereby the threads will be injured by said points. With coarse 35 threads this incident is immaterial but when weaving fine fabrics frequent ruptures of the warp threads will be caused thereby, and the utilization of the above described device for weaving silk goods is therefore excluded.

40 This disadvantage is overcome according to the present invention by swinging the comb at first away from the point where the beating up of the weft occurs and withdrawing the teeth of the comb from the

warp by a downward movement of the 55 comb at a point which is at a comparative great distance from the beating up point; at this remote point the swinging back movement of the warp threads into their normal position is so small and 60 occurs with little force so that the latter are not injured.

The oscillating movement of the comb between the batten and the beating up point is 65 preferably caused by a toothed gearing, the gear element with the smaller diameter being fixed to the rocking shaft, whereas the cooperating gear element having the larger diameter is loosely mounted on the shaft about which the rocking shaft swings in the 70 vertical direction the oscillating motion of the second gear element being derived independently from the movement in the vertical direction of said shaft.

75 One constructional example of the weaving loom according to the present invention is illustrated on the accompanying drawings, in which:

Fig. 1 is a vertical section of the loom.

Fig. 2 is a plan-view with parts omitted,

Fig. 3 is a detail on an enlarged scale of the comb,

Figs. 4-7 show details of parts of the loom in different working positions.

Referring now to the drawings 1 denotes 85 the batten which is provided with the reed 2 by means of which the warp threads 3 are guided. A shuttle way is arranged in the batten 1 in which the shuttle 4 is movable in a horizontal plane in order to lay 90 the weft in a known manner. The means for beating up the weft comprises a comb 5 provided with claw shaped teeth 6, the teeth being curved towards the beating up point S. The single teeth are inserted in a plate fixed to the shaft 7, the distancing between adjacent teeth being effected by the coils of a wire 5' (Fig. 3).

The comb 5 is arranged below the warp threads and is carried by a rocking shaft 7 which is loosely mounted in arms 8 fixed to a shaft 9 which is rotatably mounted in the loom frame 10. To the ends of the rocking shaft 7 eccentrics 11 are fixed against which the batten 1, which is pivotally 105 mounted by arms 12 swinging about the fulcrum pins 13, is urged by the pressure of the coil spring 14, abutment plates 14'

(shown in detail in Fig. 5) for cooperation with the eccentrics 11 being provided on the shuttle boxes 15 of which one is shown in Fig. 2.

- 5 A toothed gearing is interposed between the shaft 9 and the rocking shaft 7, which consists of a pinion 16 fixed to the rocking shaft 7 and of a toothed segment 17 cooperating with said pinion and being loosely
 10 mounted on the shaft 9 and having a lever 18 extending in the downward direction. The extreme end of lever 18 is linked by the connecting rod 19 to a crank 20 (Figs. 1 and 2) secured to a countershaft 21 which is rotatably mounted in the loom frame 10. From the main driving shaft 22 rotation is imparted to the countershaft 21 by the pair of gear wheels 23, 24 providing for a speed ratio of 2:1. During each revolution of the
 15 countershaft 21 the crank causes a swinging motion of the toothed segment 17 whereby the comb 5 is caused to oscillate about the shaft 7 towards the beating up point S and back towards the batten.
 20 A movement of the comb 5 in the transverse direction of the loom is further effected by means described hereinafter. To provide for this transverse movement the connection between the lever 18 and the connecting rod 19 comprises twin arms 18' in which a pin 26 is carried. The width of the head 27 of the connecting rod 19 embracing the pin 26 is smaller than the clear width between the arms 18' so that clearance is provided to permit of a movement
 25 of the shaft 9 that is transverse to the loom or in the longitudinal direction of the shaft 9 and of the lever 18 without causing a jamming of the connecting rod 19. To secure the connecting rod 19 against taking part in the longitudinal movement of the shaft 9 the rod 19 is provided with an extension 28 which projects into a guide part 29 (Fig. 7), the width of which corresponds to the thickness of the extension 28, the height of which, however, is larger than the respective dimension of the extension in order to permit of a movement of the latter in the vertical direction.
 30 On the shaft 9 an arm 30 is fixed, the end of which is linked by means of the connecting rod 31 to a rocking lever 32 pivotally mounted at 33 in the loom frame 10. The free end of the lever 32 is provided with a roller 34 that cooperates with a cam 35 fixed to the countershaft 21. A coil spring 36 causes the roller 34 to continuously bear against the cam 35. In order to provide for the transverse movement of the comb 5 and of the shaft 9 the connection between one end of the connecting rod 31 and the lever 32 is provided with a Cardan joint 25. Upon every revolution of the countershaft 21 an oscillating movement of the shaft 9 is caused by the action of the parts

30—35 which again causes a to and fro movement of the shaft 7 and of the comb 5 in the vertical direction.

The means for imparting to the comb 5 a movement in the transverse direction of the loom cause a movement of the shaft 9 in the longitudinal direction thereof and comprise the following parts, which are shown in detail in Fig. 6.

75 A screw wheel 36' is fixed to the countershaft 21 and is in engagement with a screw wheel 37 secured to a shaft 38, the other end of which is provided with a cam 39. A roller 40 mounted in the end of one arm of bell crank lever 41 cooperates with the cam 39. The bell crank lever 41 is swingably mounted about a fulcrum 42 carried in a bracket 43 and to the other arm of the bell crank lever 41 there is connected a rod 44 which is linked at its other end to a pin 45 fixed on a collar 46 that is secured to the shaft 9. A compression spring 46' causes the roller 40 to bear against the cam 39.

90 The harnesses 47 and 48 are shown in their respective position when the shed is open. The means for causing the movement of each harness are not shown in detail as they are well known and do not form part of the present invention. The woven fabric passes over rolls 49 and 50 and is wound upon the cloth beam 51. The shuttle 4 is provided with a projecting part 52 which causes the weft thread to be laid nearer to the beating up point.

95 The operation of the above described loom is as follows:

100 When a weft thread has been laid into the open shed by the movement of the shuttle along the shuttle race the comb 5 is swung by the action of the crank 20, the connecting rod 19 and the toothed gearing 17, 16 from the position shown in Fig. 1 towards the beating up point into the position shown in Fig. 4 and simultaneously the rocking shaft 7 which carries the comb 5 is moved in the upward direction by the action of cam 35, rocking lever 32, connecting rod 31 and levers 30 and 8 on shaft 9. Thereby the teeth of the comb 5 enter between the warp threads at the rear of the weft thread and beat the latter up to the fabric. The comb 5 is thereafter swung back towards the batten 1 and performs at the same time a movement in the downward direction, whereby the tips of the comb leave the warp threads at a point near the batten in which the warp threads are at such a distance from each other that this distance is not much increased by the comb, the relieved warp threads will not move against each other with great force, so that ruptures of the warp threads are avoided. The vertical movement of the comb is the cause that the teeth remain for a shorter time between

the warp threads than if the comb would only carry out a swinging movement. Obviously the shorter time the teeth of the comb remain in between the warp threads 5 the more time is available for the other operations of the loom and the greater the speed of the loom. The claw shape of the teeth of the comb presents the advantage that the weft thread is securely gripped 10 when being beaten up. The curvature at the rear of the teeth of the comb 5 (Fig. 3) prevents damage to the teeth, when the teeth should incidentally strike against the shuttle, the latter is pushed away by the teeth. 15 During the oscillating movement of the rocking shaft 7 the eccentrics 11 push the batten 1 back to a small extent. Thereby the following result is attained: When the comb 5 moves towards the beating up point 20 S it tends to push forward any warp thread that is broken behind the reed 2. This may cause that such threads come to lie transversely to the normal warp threads so that they can hinder the passage of the shuttle 25 and cause other interruptions of the loom. The backward movement of the batten counteracts the tendency of the comb 5 to push the threads forward as the latter are moved in the backward direction by the reed 30 2.

The movement of the comb 5 in the transverse direction of the loom effected by the screw-wheels 36, 37, shaft 38, cam 39, roller 40, bell crank lever 41 and link 44 serves the 35 following purpose: It is practically impossible to attain a mathematically correct uniformity of the teeth of the comb 5 and of the reed 2, therefore the distance of the warp threads from each other will not be 40 uniform across the whole width of the warp. This lack of uniformity will be noticed in the finished fabric. The transverse movement of the comb 5 has the effect that the same teeth of the latter do not occupy the 45 same place in the warp but change their places whereby an equalizing effect and a better uniformity of the finished fabric is attained. Any discrepancy in the distance of the individual teeth of the comb 5 and 50 of the reed 2 is also equalized by this transverse movement of the comb 5. The eccentric 39 is preferably of such a shape that the shifting of the comb is not uniform but is alternately carried out to a larger or 55 smaller degree. The larger shifting movement serves to prevent faulty parts in the woven fabric that result from the lack of uniformity of the teeth of the comb and reed and the smaller shifting movement serves to 60 overcome faults resulting from other reasons.

I claim:

1. In a loom for weaving fine fabrics, the combination of a batten, a reed on said batten for guiding the warp threads, a comb, 65 a rocking shaft on which the comb is mount- ed, a second shaft parallel to said rocking shaft and carrying the rocking shaft, means to operate the rocking shaft from the parallel shaft to move the comb into and out of the warp at a point that is at a considerable 70 distance from the beating-up point.

2. In a loom for weaving fine fabrics, the combination of a batten, a reed on said batten for guiding the warp threads, a comb for beating up the weft, a rocking shaft on which said comb is fixed arranged below the beating up point, a second shaft arranged parallel to the rocking shaft and carrying the latter, a pinion on the rocking shaft, a toothed segment on the second shaft co-operating with said pinion, means to impart an oscillating movement to said toothed segment, and means to simultaneously move said rocking shaft up and down in the vertical direction so that the teeth of the comb 80 are withdrawn from the warp at a point that is at a considerable distance from the beating up point.

3. In a loom for weaving fine fabrics, the combination of a batten, a reed on said batten for guiding the warp threads, a comb for beating up the weft, a rocking shaft on which said comb is fixed arranged below the beating up point, a second shaft arranged parallel to the rocking shaft and carrying the latter, a pinion on the rocking shaft, a toothed segment on the second shaft co-operating with said pinion, means to impart an oscillating movement to said toothed segment, means to simultaneously move said rocking shaft up and down in the vertical direction so that the teeth of the comb are withdrawn from the warp at a point that is at a considerable distance from the beating up point, eccentrics mounted on the rocking 90 shaft, and a spring for pressing the batten against said eccentrics, the batten being pushed backwards by said eccentrics when the rocking shaft oscillates.

4. In a loom for weaving fine fabrics, the combination of a batten, a reed on said batten for guiding the warp threads, a comb for beating up the weft, a rocking shaft on which said comb is fixed arranged below the beating up point, a second shaft arranged parallel to the rocking shaft and carrying the latter, a pinion on the rocking shaft, a toothed segment on the second shaft co-operating with said pinion, means to impart an oscillating movement to said toothed segment, means to simultaneously move said rocking shaft up and down in the vertical direction so that the teeth of the comb are withdrawn from the warp at a point that is at a considerable distance from the beating up point, and means to impart to the second shaft and thereby to the comb a displacement in the transverse direction of the 110 loom.

5. In a loom for weaving fine fabrics the 115

combination of a batten, a reed on said batten for guiding the warp threads, a comb for beating up the weft, a rocking shaft on which said comb is fixed arranged below the 5 beating up point, a second shaft arranged parallel to the rocking shaft and carrying the latter, a pinion on the rocking shaft, a toothed segment on the second shaft cooperating with said pinion, means to impart an oscillating movement to said toothed segment, means to simultaneously move said 10 rocking shaft up and down in the vertical direction so that the teeth of the comb are withdrawn from the warp at a point that is 15 at a considerable distance from the beating up point, and means to impart to the second shaft and thereby to the comb a varying displacement in the transverse direction of the loom after every few operations of the comb.

20 6. In a loom for weaving fine fabrics, the combination of a batten, a reed on said batten for guiding the warp threads, a comb for beating up the weft, a rocking shaft on

which said comb is fixed arranged below the beating up point, a second shaft arranged 25 parallel to the rocking shaft and carrying the latter, a pinion on the rocking shaft, a toothed segment on the second shaft cooperating with said pinion, means to impart an oscillating movement to said toothed segment, means to simultaneously move said 30 rocking shaft up and down in the vertical direction so that the teeth of the comb are withdrawn from the warp at a point that is at a considerable distance from the beating 35 up point, eccentrics mounted on the rocking shaft, and a spring for pressing the batten against said eccentrics, the batten being pushed backwards by said eccentrics when the rocking shaft oscillates, and means to 40 impart to the second shaft and thereby to the comb a varying displacement in the transverse direction of the loom after every few operations of the comb.

In testimony whereof I affix my signature.
ATTILIO ZANCHI.
